BRAKE

Filed Jan. 19, 1928

INVENTOR

VINCENT BENDIX

BY

Dr. W. M. Conkey

ATTORNEY

UNITED STATES PATENT OFFICE

VINCENT BENDIX, OF CHICAGO, ILLINOIS, ASSIGNOR TO BENDIX BRAKE COMPANY,
OF SOUTH BEND, INDIANA, A CORPORATION OF ILLINOIS

BRAKE

Application filed January 19, 1928. Serial No. 247,798.

This invention relates to brakes, and is illustrated as embodied in a novel internal expanding brake for an automobile. An object of the invention is to provide a very powerful brake of the "servo" type, preferably fully effective in either direction of drum rotation, of a simple and inexpensive design.

An important feature relates to the operation of anchored friction means, preferably including a pair of anchored shoes, by means of a servo shoe moving with the drum into direct thrust engagement with one or the other of the shoes. In one very efficient embodiment, at least one of the anchored shoes, when applied by the servo shoe, is arranged to apply the other anchored shoe. As illustrated, this is accomplished by providing one of the anchored shoes with a thrust portion extending beyond the anchor and operatively engaged by the other shoe.

Other features of novelty relate to providing the servo shoe, or some equivalent shoe, with novel spaced parts guidingly embracing the end of an adjacent shoe, to a novel applying device shown as including a roller having a novel mounting and engaging the edge of the shoe stiffening web, and to other novel and desirable structural features which will be apparent from the following description of the illustrative embodiments shown in the accompanying drawing, in which:

Figure 1 is a vertical section through the brake, just inside the head of the brake drum, showing the shoes in side elevation;

Figure 2 is a partial elevation corresponding to the lower part of Figure 1, and showing a modification; and

Figure 3 is a section on the line 3—3 of Figure 1, showing the novel roller mounting.

The illustrated brake includes a rotatable drum 10, at the open side of which is a support such as a backing plate 12, and within which is arranged the friction means of the brake.

The novel friction means shown in Figure 1 includes a pair of anchored shoes 14 and 16, the torque of which is taken by a

pivot 18 at one side of the drum. Shoe 14, reinforced if desired by welding separately-formed plates 20 to opposite sides of its stiffening web, is pivoted directly on the anchor 18, and preferably has a thrust portion 22 on the opposite side of the anchor from its friction face, which portion has a semi-circular bearing embracing a floating pivot 24 engaged by a similar bearing in the end of the shoe 16. A return spring 26 urges the shoes away from the drum and also holds the two shoes against pivot 24. Shoe 16 may also, if desired, be reinforced by separately-formed plates 28 welded to its opposite sides.

It will be seen that if the brake is applied with the drum turning counter-clockwise, shoe 16 thrusts through pivot 24 in a direction to turn shoe 14 about pivot 18 against the drum. The positions of the shoes 14 and 16, with the brake released, may be determined by suitable stops 30, illustrated substantially as described in application Serial No. 145,189, filed October 30, 1926, by Adiel Y. Dodge. Preferably the shoes 14 and 16, or their equivalents, are applied by means including a novel floating friction servo shoe 32, which may have rounded ends in direct thrust engagement with the rounded ends of shoes 14 and 16. The ends of the stiffening web of shoe 32 are shown with spaced parts, such as separately-formed plates 34 projection-welded to the sides of the web, which parts guidingly embrace the ends of shoes 14 and 16.

When the drum is turning clockwise, the servo shoe 32 acts against shoe 14, and when the drum is turning counterclockwise the servo shoe acts against shoe 16. When mounted on an automobile, I prefer that the drum in Figure 1 should turn counterclockwise when the car is moving forward.

The servo shoe 32 is applied, against the resistance of two return springs 36, by novel means such as a thrust roller 38 mounted on a pivot 40 carried by a pair of arms 42 and 44 mounted on an operating shaft 46. Cotter pins 48, or other suitable devices, are provided to hold pivot 40 against axial movement. Washers 50, of larger diameter

than roller 38, are mounted on pivot 40 between arms 42 and 44, on opposite sides of roller 38, and guidingly embrace the lower portion of the web of shoe 32.

- 5 The web may be reinforced at this point, if desired, by plates 52 projection-welded to its sides, the web and plates 52 having their inner edges ground or otherwise formed on an arc engaged by roller 38, and which arc 10 preferably has its center arranged (when the brake is applied) at the center of the drum 10.
12. In the arrangement of Figure 2, shoes 114 and 116 are formed at their adjacent ends 15 with semicircular sockets embracing a fixed pivot or anchor 118. In this arrangement the articulation 24 is omitted.

While two illustrative embodiments have been described in detail, it is not my intention to limit the scope of the invention to those particular embodiments, or otherwise than by the terms of the appended claims.

I claim:

1. A brake comprising, in combination, an anchor, a first shoe engaging the anchor and having its friction face on one side of the anchor and having a thrust portion extending on the opposite side of the anchor, a second shoe acting on said thrust portion to 20 apply the first shoe, and servo friction means for actuating the second shoe.

2. A brake comprising a pair of shoes arranged end to end and having alined stiffening webs in direct thrust engagement with 25 each other, and one of which shoes has spaced parts carried by and projecting beyond the end of its stiffening web and guidingly embracing the web of the other shoe.

3. A brake comprising a pair of shoes arranged end to end including alined stiffening webs having direct thrust engagement and one of which shoes has spaced separately-formed plates secured to and projecting beyond the end of its stiffening web and 45 guidingly embracing the web of the other shoe.

4. A brake including three shoes arranged end to end, and formed with alined stiffening webs at least at their adjacent ends, the 50 web of one of the shoes having direct thrust engagement with the webs on the other shoes and having spaced parts guidingly embracing the other shoes.

5. A brake shoe having at both ends pairs 55 of separately-formed plates secured thereto to form spaced projecting arms.

6. A brake comprising a shoe having a stiffening web, in combination with an applying roller operatively engaging the edge 60 of said web and having parts projecting at opposite sides of the roller and guidingly embracing said web.

7. A brake comprising a shoe having a stiffening web, in combination with an applying device operatively engaging said web 65

and having parts guidingly embracing said web.

8. A brake-applying device including a pair of spaced arms carrying a pivot and a thrust roller mounted on the pivot between 70 said arms.

9. A brake-applying device including a pair of spaced arms carrying a pivot, a thrust roller mounted on the pivot between said arms, and a pair of guide washers of 75 greater diameter than the roller mounted on the pivot between said arms on opposite sides of the roller.

10. A brake comprising, in combination, an anchor, a first shoe engaging the anchor and having its friction face on one side of the anchor and having a thrust portion extending on the opposite side of the anchor, and a second shoe acting on said thrust portion to apply the first shoe.

11. A brake comprising, in combination, an anchor, a first shoe engaging the anchor and having its friction face on one side of the anchor and having a thrust portion extending on the opposite side of the anchor, 90 means acting on said thrust portion to apply the first shoe, and servo friction means for actuating said means.

In testimony whereof, I have hereunto signed my name.

VINCENT BENDIX.
